UNITED STATES PATENT OFFICE.

JOHN J. HOGAN, OF BROOKLYN, NEW YORK, ASSIGNOR TO THE HOGAN
ENGINEERING COMPANY, OF NEW YORK.

BOILER WITH TRAPPED CIRCULATION.

SPECIFICATION forming part of Letters Patent No. 425,944, dated April 15, 1890.

Application filed December 9, 1889. Serial No. 338,145. (No model.)

To all whom it may concern:

Be it known that I, JOHN J. HOGAN, a citizen of the United States, residing at Brooklyn, Kings county, New York, have invented 5 certain new and useful Improvements in Boilers with Trapped Circulation, fully described and represented in the following specification and the accompanying drawings, forming a part of the same.

10 My invention is particularly adapted for heating water to circulate through radiators, in which case the generation of steam in the boiler is undesirable; and its object is to promote an upward circulation within the boiler over the hottest part of the fire, and a positive downward circulation exterior to the water-space of the boiler to replace the rising fluid. The upward circulation is preferably conducted through a passage in the center of 15 the boiler, because such point is over the hottest part of the fire, and the fluid moving downward is led to conductors exterior to the boiler, that such conductors may be cooler than the water-space of the boiler and thereby promote 20 the movement of the fluid downward therein. The exterior conductors are connected to the water-space of the boiler at intervals by connections leading downwardly from such water-section into such conductor. The passage be- 25 tween the water-space and the exterior conductor may be confined to the lower part of each water-section by leading the water channel or connection from the bottom of such water-space, or by a deflecting plate or tube 30 projecting downwardly within the upper part of such water-space, where it is connected with the exterior conductor. Each of these constructions serves alike to trap the hot water within the water-section and prevent its ris- 35 ing into the exterior conductor, while the connection with the exterior conductor permits the free access of colder fluid from the conductor to the water-section, as may be required. By this construction the heated fluid within 40 the boiler is prevented from gaining access to the exterior conductors and thus obstructing the downward current therein, and is effect- 45 ively directed toward the vertical passage or 50 passages within the water-space in which the current moves naturally upward.

Cast-iron boilers have heretofore been made in horizontal sections with vertical connecting-thimbles, and the exterior of such sections has been made sometimes round and sometimes rectangular to form a circular or a square 55 boiler.

My improvements are especially adapted to boilers formed with horizontal water-sections and intermediate smoke-chambers, but may obviously be applied to other constructions. 60

In the annexed drawings, Figure 1 is an elevation of a boiler constructed with my improvement in horizontal water-sections with intermediate smoke-chambers. Fig. 2 is a central vertical section of the same. Fig. 3 is a 65 plan of the same at the top of the fire-pot. Fig. 4 is a plan, partly in section where hatched, of the sections above the fire-box, excepting the top one. Fig. 5 is a section, upon an enlarged scale, of part of two sections, with 70 the external thimbles projected downward therein; and Fig. 6 is a similar view of two sections, with deflectors upon their upper sides adjacent to the thimbles.

A B C D are four water-sections separated 75 by smoke-spaces e and sustained above a fire-pot by a series of water-columns p and l. The fire-pot is formed by a water-ring E and rests upon an ash-pit F, provided with grate G.

Each water-section, except the section T (if 80 such be used) at the extreme top of the boiler, is provided with apertures b, which are ex- tended over one another in the same vertical line to form continuous vertical smoke-flues connecting the fire-box and the intermediate 85 spaces e directly with the upper smoke-space H, from which the smoke is conducted by a nozzle I. Each water-section is also provided with smoke-apertures b', formed to alternate with one another in the several sections A B 90 C D, and thus form interrupted smoke-flues, such as have been commonly used in similar constructions. A hollow ring containing an annular water-space j projects downward from the bottom of each water-section at its mar- 95 gin, and is provided with hollow lugs k, which are connected together by thimbles l, arranged in vertical line over one another. The inter- 100iors of the water-sections are connected together at the center by circular nozzles n,

forming a vertical water column or passage p over the center of the fire-box, and the outlet o of the boiler is provided in the top section over such central passage to discharge the 5 heated fluid in an unbroken current.

The top section T is shown as constructed merely to cover the top smoke-space with a water-box, and the return-fluid from the heating-radiators would be connected by pipes q 10 with the lugs k in such top section, and also with the water-ring E around the fire-pot by a nozzle q' intermediate to the lugs k' , formed upon the same. A smoke-aperture I' is extended through the top section to connect the 15 boiler to a chimney-flue by a suitable pipe I .

The lugs k' , formed upon the water-ring E , are arranged in line with the corresponding lugs upon the water-sections, and are connected thereto by the thimbles l , which form 20 an uninterrupted vertical column or passage for the descent of the colder fluid. The water-ring is also connected with the lower part of the ring j upon the section A by tubular connections s , which provide a passage for 25 the upward movement of the fluid heated within the water-ring. The ring is partially lined with fire-brick b^2 , and an aperture a for a fire-door is formed in such ring above the fire-brick and in a portion of the annular 30 ring j upon the lower edge of the section A , as shown in Figs. 1 and 3.

It will be noticed that the apertures b through the water-sections being in a direct line with one another induce a strong draft 35 from the fire upward to the top smoke-space H , and thus operate to heat most effectively the central water-passage p , while the thimbles l being wholly removed from the action of the fire operate as uninterrupted descending 40 columns for the colder fluid. When the return-current from a system of heating-radiators is connected with the nozzle q' upon the water-ring it is immediately heated by the 45 heat of the fire-box and rises through the connections s into the water-section above it.

The only connection from each of the water-sections with the thimbles l is through the annular water-spaces j , which are connected exclusively with the bottoms of the 50 sections, and the water heated in the several sections is thus forced to move exclusively toward the central water-channel p to rise upward in the boiler. The movement of the heated fluid toward the center 55 of the boiler is facilitated by sloping the top of each of the water-sections upwardly toward the nozzle n , as shown in Fig. 2. Here the central water-column furnishes a direct upward passage for the heated fluid, which is 60 thus led to the outlet o in the top section. The margin of the section (shown at A' in Fig. 2) thus operates as a trap to obstruct any upward movement of the water within the water-sections toward the thimbles l , while it 65 does not in the least impede a downward movement of the water from any of the sections to the thimbles. When the return-fluid

from the circulating system outside of the boiler is cut off from the boiler, the heat around the fire-pot would soon overheat the 70 adjacent surfaces and injure the metal unless a free circulation of water be maintained therein. By the trapped formation of the connections between the water-sections and the thimbles l a positive upward circulation 75 is induced in the center of the boiler, and a positive downward circulation is induced in the thimbles. It will also be noticed by reference to Fig. 2 that, while the trapped connection referred to impedes the movement of 80 the hot water in any of the water-sections toward the lugs k , it offers no obstruction to the rising of the fluid from any of the lugs into the water-section, as would be required in the case of the section A , which receives 85 all the return-fluid from the water-ring through the connections s and lower thimbles l .

Fig. 5 shows the lug k projected directly from the edge of the water-section without 90 any depending water-space j , and the trapped connection between the water-section and the thimble is formed by projecting the end of the thimble downward within the top of the section, as shown at l' . Such construction 95 does not obstruct the downward flow of the current in the thimbles nor the upward movement of the fluid from the thimbles into the water-section, while it does obstruct, in the desired manner, the passage of hot water from 100 the upper side of the water-section to the upper thimble.

In Fig. 6 a deflector l^2 is shown formed across the lug k between the inlet of the thimble and the body of the water-section, and thus 105 performs the same function as the projecting end of the thimble shown at l' in Fig. 5.

It will be noticed that all the constructions shown in Figs. 2, 5, and 6 operate alike as deflectors projected downward in the connections between the water-sections and the external conductor or thimble, and thus prevent 110 the upward movement of the fluid from the water-space to the conductors. The water-connection from the section to the interior of 115 the projecting lug k may thus be said to lead downwardly, and furnishes a passage opposed to the outward movement of the heated fluid, which more naturally moves upward within 120 the boiler under the pressure of the colder fluid, which may press upon it.

While the smoke-apertures b' , by their arrangement in the several sections, obstruct the direct flow of the heated gases, the apertures b serve to carry the heated gas from the 125 fire-pot directly upward in close contact with the central water-channel p , and I therefore consider the combination of such direct and indirect smoke-passages as serving a valuable purpose in connection with the trapped circulation of the boiler.

Fig. 4 is drawn in section at the right-hand side to show the water-space between the apertures b and b' and to exhibit a guard w , which

- is shown extended within the margin of the section at the inner edge of the depending hollow ring, which forms the annular water-space *j*. This guard, when used, operates to prevent the direct flow of the fluid to or from the thimbles *l*, and compels the circulation from the thimbles to the central nozzles to pass around the ends of the guard to reach the latter.
- 10 I find a great advantage in the sloping top upon each of the water-sections, as shown in Figs. 2, 5, and 6, when used in combination with the external conductors, which are connected with such sections by the downward 15 passages employed in my construction. By such construction and by the provision of a large vertical passage within the boiler like the central water-column *p*, I furnish ample facilities for the upward movement of the 20 water over the hottest part of the fire; while the exterior conductors furnish a suitable channel or water-column for the downward movement of the fluid to maintain a circulation within the boiler when the disuse of the 25 external heating system necessitates such a circulation. I thus wholly prevent the over-heating of the boiler in any part, while I increase its evaporative power.
- The hollow ring shown herein projected 30 downward from the margin of each section is made circular in form to correspond with the shape of the section; but it is obvious that such ring is in function a water-leg, and that a precise equivalent for such hollow ring 35 could be formed upon the margin of a square section and projected downward, and furnished with connections to the external conductors in the manner herein described. I therefore consider that a water-leg, formed 40 upon a square rim, and connected like the hollow ring shown in my drawings, would be a precise equivalent therefor, and would be covered by my claims herein.
- I hereby disclaim my pending application 45 No. 332,697, filed December 5, 1889, as I have shown and described herein certain features which are claimed in the said application.
- In my pending application, Serial No. 332,697, filed December 5, 1889, I have shown 50 a boiler constructed substantially like that in my present drawings, and have claimed a water-jacket connected with the edge of each section and two or more vertical water-connections between the sections to provide for 55 upward and downward circulation. I have also claimed in connection with such water-jacket a vertical water-connection between the sections inside the same and a vertical water-connection between the sections external 60 to the same, and to such constructions I make no claim in my present application.
- Having thus set forth my invention, what I claim herein is—
1. In a boiler, the combination, with one or 65 more water-passages extending vertically within the boiler, of one or more water-conductors exterior to the water-space of the
- boiler, connections at intervals between the external conductors and the water-space of the boiler, and deflectors projected downward 70 in such connections to prevent the upward movement of fluid from the water-space to the conductors, substantially as herein set forth.
2. In a boiler comprising a series of water-sections separated by intermediate smoke-chambers, the combination, with one or more water-passages extending vertically within the boiler, of one or more water-conductors exterior to the water-space of the boiler, connections 75 between the external conductors and the water-sections, and deflectors projected downward in such connections to prevent the upward movement of the fluid from the water-space to the conductors, substantially as herein set forth.
3. In a boiler comprising a series of water-sections separated by intermediate smoke-chambers, the combination, with a water-passage extending vertically within the boiler 80 through the centers of the water-sections, of one or more water-conductors exterior to the water-space of the boiler, connections between the external conductors and the water-sections, and deflectors projected downward 85 in such connections to prevent the upward movement of the fluid from the water-space to the conductors, substantially as herein set forth.
4. In a cast-iron boiler, the combination of 90 a series of horizontal water-sections having one or more vertical passages connecting the same for the internal upward movement of the fluid, and each section being provided with exterior lugs connected by thimbles, and 95 the water-connection between the section and the interior of such lug leading downwardly, as and for the purpose set forth.
5. In a cast-iron boiler, the combination of 100 a series of horizontal water-sections having central water-connections for the upward 105 passage of the fluid, and exterior water-connections for the downward passage of the fluid, one series of smoke-apertures through all the sections in the same vertical line to 110 form uninterrupted smoke-flues, and a series of apertures arranged alternately in the several sections to form interrupted smoke-flues, as and for the purpose set forth.
6. In a cast-iron boiler, the combination, 115 with a series of horizontal water-sections having apertures through them for the passage of smoke, and one or more vertical passages connecting the said sections for the upward movement of the fluid, of a hollow ring projected 120 downward from the margin of each section, and water-connections between such depending rings for the downward movement 125 of the fluid, as and for the purpose set forth.
7. In a cast-iron boiler, the combination of 130 a series of water-sections perforated with vertical smoke-apertures, and provided at the center with nozzles to form a vertical water-passage, the sections having external hollow

lugs connected in a series by means of thimbles, and being provided with guards *w* within the margin of the sections adjacent to such lugs to prevent the direct passage of the fluid 5 to the thimbles, substantially as herein set forth.

8. The combination, in a boiler, of a series of water-sections having domed or sloping tops, with water-connections forming a continuous passage through the centers of the sections, and vertical water-conductors ex-

terior to the sections with passages leading downwardly from each section into such exterior conductors, substantially as herein set forth. 15

In testimony whereof I have hereunto set my hand in the presence of two subscribing witnesses.

JOHN J. HOGAN.
